[57] CLAIM

The ornamental design for a paint pot and paint well, as shown and described.

DESCRIPTION

FIG. 1 is a top plan view of a paint pot and paint well showing my new design;

FIG. 2 is a front elevational view thereof with one of the paint pot covers pivoted upward in the open position as shown in phantom;

FIG. 3 is a right side elevational view of the paint pot and paint well shown in FIG. 1;

FIG. 4 is a rear elevational view of the paint pot and paint well;

FIG. 5 is a bottom plan view of the paint pot and paint well;

FIG. 6 is a left side elevational view of the paint pot and paint well;

FIG. 7 is a top plan view of a paint well showing my new

design, the paint well shown separately for convenience of

illustration;

FIG. 8 is a front elevational view of the paint well shown

separately for convenience of illustration;

FIG. 9 is a right side elevational view of the paint well

shown separately for convenience of illustration;

FIG. 10 is a rear elevational view of the paint well shown

separately for convenience of illustration;

FIG. 11 is a bottom plan view of the paint well shown

separately for convenience of illustration;

FIG. 12 is a left side elevational view of the paint well

shown separately for convenience of illustration;

FIG. 13 is a top plan view showing the paint pot of my new

design shown separately for convenience of illustration;

FIG. 14 is a front elevational view of the paint pot shown

separately for convenience of illustration;

FIG. 15 is a bottom plan view of the paint pot shown

separately for convenience of illustration;

FIG. 16 is a rear elevational view of the paint pot shown

separately for convenience of illustration;

FIG. 17 is a left side elevational view of the paint pot shown

separately for convenience of illustration; and

FIG. 18 is a right side elevational view of the paint pot

shown separately for convenience of illustration;

FIG. 19 is a perspective view of the paint pot and paint well

of FIG. 1; and,

FIG. 20 is an exploded perspective view of the paint pot and

paint well of FIG. 1.
